[57] CLAIM

The ornamental design for a combined toy spaceship
and figure therefor, as shown and described.

DESCRIPTION

FIG. 1 is a top plan view of a combined toy spaceship
and figure therefor showing my new design;

FIG. 2 is a bottom plan view thereof;

FIG. 3 is a front elevational view thereof with the leg
members in an extended position;

FIG. 4 is a rear elevational view thereof with the leg
members retracted;

FIG. 5 is a side elevational view thereof;

FIG. 6 is a side elevational view thereof with the figure
removed, the top in an opened position and the hose
member in an attached condition;

FIG. 7 is a side elevational view thereof with the top in
an opened position, and,

FIG. 8 is a rear elevational view of the figure member.
